POWDER SPRAY GUN

George B. Mornik, Mounds View Township,
Ramsey County, Minn.

Application January 13, 1950, Serial No. 138,349

16 Claims. (Cl. 169—33)

1

This invention relates to new and useful improvements in powder or dust guns and more particularly to such a gun capable of expelling or discharging a liberal quantity of powder at each discharge stroke of its operating member, whereby the gun may be utilized for smothering and extinguishing fires, when loaded with a suitable fire extinguishing powder.

An object of this invention is to provide a powder gun of such construction that the application of several or more rotary twists to the operating member will condition the gun for the expulsion of liberal quantities of powder, regardless of the extent to which the powder becomes compacted during its confinement in the gun.

Another object of the invention is the provision of a powder and air passage chamber between the discharge end wall of the gun and an easily removable inner partition.

Another object of the invention resides in the use of an air tube which provides a means of conducting air from an orifice in the inner partition to a telescoping air chamber created by the reciprocating movement of the operating member over the outer wall of the powder chamber.

Another object of the invention is the utilization of a valve in conjunction with the air tube, whereby on the air intake stroke of the operating member a full charge of air is drawn through the air tube, whereas on the discharge stroke the valve closes, and an aperture in the valve body permits only a portion of the air to re-enter the air tube.

Another object of the invention resides in the provision of a discharge nozzle sealing plug integrally extended to form a closure for the orifice in the inner partition and thereby prevent powder from entering the air tube when the gun is inoperative, the plug being connected to the operating member by means of a flexible element, so that on withdrawal of the operating member, as on the intake stroke, the plug will automatically be pulled out and expose a continuous opening for the easy access of air into the air tube.

Another object of the invention resides in the construction of the valve which controls the flow of air from the telescoping air chamber to the powder chamber.

A further object of the invention is to provide a device in the form of a pronged member attached to a portion of the air tube near the valve which controls the flow of air from the telescoping air chamber to the powder chamber, therefore by relatively twisting the operating member the air tube will turn and cause the prong to loosen

2

any compacted powder pressing against the valve and permit the valve to operate.

A further object of the invention resides in the distribution of a plurality of powder and air passage ducts disposed longitudinally at the inner wall of the powder chamber, the ducts being open on each end to permit the passage of powder and air from the powder chamber to the passage chamber.

10 A still further object of the invention is the provision of a plurality of apertures distributed along the wall of each of the powder and air passage ducts, said apertures providing a means of communication between the powder chamber and ducts.

15 Another object of the invention is the provision in the discharge end wall of the gun a single nozzle for powder discharge and air intake, said nozzle cooperating pneumatically with the inner orifice in the inner partition, therefore on the intake stroke air is introduced into the air tube by passing consecutively through the nozzle, powder and air passage chamber, and inner orifice, whereas on the discharge stroke a powder 20 in air dispersion is expelled from the discharge nozzle by the combined action of the powder and air mixture coming from the plurality of powder and air passage ducts and an air stream coming from the inner orifice.

25 30 These and other objects of the invention and the means for their attainment will be more apparent from the following description taken in connection with the following drawings.

In the accompanying drawings there has been disclosed a structure design to carry out the various objects of the invention.

In the drawings:

Figure 1 is a longitudinal sectional view on the line 1—1 of Figure 3, showing the parts in their normal position, as when the gun is sealed;

40 Figure 2 is a longitudinal view with the gun in the same position as in Figure 1, but with parts broken away to show the operating member turned one quarter turn to the right and partially withdrawn to release the plug closure for the nozzle and inner orifice, and also showing the air tube turned one quarter turn to the right, both aforementioned turns being considered turns to the right when the discharge end of the gun, known as the forward end, is held away from the operator and the opposite end, known as the rear end, is held toward the operator;

45 50 Figure 3 is a view showing the discharge end of the gun having a portion of the cover broken away to show the inner partition position retaining

lugs, and also showing the forward ends of the powder and air passage ducts;

Figure 4 is a cross sectional view on the line 4-4 of Figure 1, showing, a centrally disposed air tube, the distribution of four equally spaced powder and air passage ducts at the inner wall of the powder chamber, and the location of four position retaining extensions attached to the inner partition;

Figure 5 is a cross sectional view on the line 5-5 of Figure 1, showing, the turning arm of the air tube, the openings in the rear end wall of the powder chamber, and the openings in the body of the flexible valve on the rear end of the air tube.

The powder gun herein disclosed comprises a main cylinder, generally designated by the numeral 1, and a removable closure in the form of a front cover 2 for the forward end of the cylinder. The front cover 2 provides a convenient means of entry into the gun when the gun is to be recharged. A short discharge nozzle 3 of circular cross section is centrally disposed in the front cover 2 and consists of a smooth sharply convergent entry portion 4 followed by a gradually divergent exit portion 5, the divergent portion being on the outer, or discharge, side of the cover. By means of this variation in the contour of the nozzle a discharge nozzle is obtained which is more efficient in operation and imparts a greater range to the discharge jet than is obtainable with the customary sharp edged orifices of this general class of powder guns. Both the cover 2 and nozzle 3 shown in Figures 1 and 2 may be constructed separately of metal, then locked together in their normal position with respect to each other by firmly pressing the curved edge 6 of the cover 2 against the outer surface of the nozzle 3 and outwardly expanding the divergent portion 5 to its desired form. It is also proposed that an alternative construction can be obtained by the formation of the cover 2 and the nozzle 3 into a single unit from a suitable plastic material.

A closure for the rear end of the main cylinder 1 consists of a back end wall 7 having a cylindrical rim 8 bent at right angles to the main body of the end wall 7. The cylindrical rim 8 is fixedly secured to the inner wall of the main cylinder 1 by the application of a cement or other suitable means of attachment.

The greater portion of the main cylinder 1 is reduced as shown at 9 to provide an annular shoulder 10 disposed intermediately of the cylinder.

An operating member, generally designated by the numeral 11, is mounted for reciprocal movement on the reduced portion 9 of the main cylinder 1, and has an end wall 12, as best shown in Figures 1 and 2. The forward motion of the operating member 11 is limited by the annular shoulder 10.

A narrow passage chamber 13 is formed between the front cover 2 and a suitably spaced inner partition 14 as best shown in Figures 1 and 2. Four inner partition position retaining lugs 15 are shown in the figures. The lugs 15 consist of raised portions of the inner partition 14 and abut against the inside face of the front cover 2 when the cover is in its normally closed position. The lugs 15 also provide a means of grasping the inner partition 14 so that it can be conveniently removed from its position in the gun.

Suitably disposed in the inner partition 14 is an inner orifice 16 of circular cross section. The

orifice 16 is comprised of a sharply convergent portion 17 integrally associated with a tubular portion 18 formed from a short tubular extension 19 of the body of the inner partition 14. The location of the inner orifice 16 with respect to the nozzle 3 is such that, in normal operation of the gun, an air jet passing through either orifice 16 or nozzle 3 will go through the passage chamber 13 and directly into the other orifice or nozzle, as the case may be. Any air stream passing through the inner orifice 16 and across the passage chamber 13 is so reduced in cross sectional area by the entrance rim of the short tubular extension 19 that the area of the jet passing through the passage chamber 13 will be less than the area of the inner orifice 16. By constricting the jet in this manner the passage of air and powder from other portions of the passage chamber 13 to the nozzle 3 will be facilitated. The relationship between the nozzle 3, inner orifice 16, and passage chamber 13, as well as the construction of each, is best shown in Figures 2 and 3.

An air tube 20 provides a means of conducting air from the inner orifice 16 to the telescoping air chamber 21. When the operating member 11 is pulled backward a partial vacuum is created in the telescoping air chamber 21, and as a result of this action air is drawn from the atmosphere into the nozzle 3 from where it passes consecutively through the passage chamber 13, the inner orifice 16, the air tube 20, and thence into the telescoping air chamber 21. The air tube is rotatably supported on the forward end by a cylindrical extension 22 of the inner partition 14 and on the rear end by an opening 23 in the back end wall 7. A projection 24 on the air tube 20 provides a stop for fixing the position of the air tube.

The portion of the air tube 20 extending into the telescoping air chamber 21, as shown at 25, is diametrically recessed at 26 to receive a turning arm 27 which extends laterally beyond each side of the air tube so that it can be engaged by two turning elements 28 diametrically opposite each other and formed from a turning member 29 fixedly attached, as by spot welding, to the end wall 12 of the operating member 11. When the operating member 11 is relatively rotated from the position shown in Figure 1, the turning elements 28 abuttingly engage opposite sides and ends of the turning arm 27 and cause the air tube 20 to revolve in its supports. By pulling back on the operating member 11 the turning elements 28 readily become disengaged from the turning arm 27 and thus permit the operating member to be manipulated in its normal reciprocating manner.

When the air in the telescoping air chamber 21 is compressed, as on the discharge stroke of the operating member 11, the bulk of the air is made to pass through a plurality of openings 30 in the back end wall 7. The resulting pressure in the openings 30 causes the soft valve member 31, normally covering the openings, to be bent away from the end wall 7 and permit the compressed air to enter the powder storage chamber 32. A stiff flexible valve member 33, constructed of paper or other suitable material, normally holds the soft valve member 31 against the openings 30 and prevents powder from entering the telescoping chamber 21. Both valve members 31 and 33 consist of circular discs with concentric holes to accommodate the air tube 20 over which they are passed, and the projection 24 provides a means of holding the valve mem-

bers in position against the end wall 7. A soft valve member is used in conjunction with a harder flexible material so as to impart resiliency to the valve combination and to provide more suitable space conforming properties to the portion of the valve in contact with the openings 30 than would be obtainable with a hard flexible material used alone.

An important feature of the invention is provided for by a plurality of powder and air tubes of which four are utilized in the disclosure herein described and which are generally designated by the numeral 34, as best shown in Figures 1 and 4. Each powder and air tube 34 is comprised of a suitable U-shaped member which forms a continuous narrow duct 35 when the member is fixedly attached longitudinally to the inner side of the outside wall of the powder storage chamber 32 by means of bent extensions 36 of the sides of the U-shaped member. The rear end of each powder and air tube 34 is in close proximity to the valve members 31 and 33, and the forward end is connected with a matched opening 37 in the inner partition 14 so as to provide a continuous duct from the rear end of the powder chamber 32 to the passage chamber 13. A plurality of suitably spaced apertures 38 in the wall of each powder and air passage tube 34 establish a means by which powder and air mixtures may pass from the powder storage chamber 32 into each of the ducts 35. The relationship between the size of the ducts 35 and the number of powder and air passage tubes 34 must be such that sufficient velocity is imparted to the powder and air stream within the ducts to effectively propel the powder and air mixture within said ducts. When the gun is held in a horizontal or slightly inclined position one or more of the powder and air passage tubes 34 will be at or near the bottom of the powder storage chamber 32, as can readily be seen from Figure 4, thereby permitting the force of gravity to act as an additional means of carrying powder into the lower ducts 35 wherein it is swept to the passage chamber 13 by the compressed air in the powder storage chamber. This is an especially useful construction for those applications in which heavy free flowing powders are to be discharged at a rapid rate.

Should the gun be stored in a vertical or inclined position with the rearward end downward and be subjected to the vibration or jarring which occurs in a moving vehicle, heavy powders will become compacted against the valve members 31 and 33 and prevent them from flexing into the open position when the air in the telescoping air chamber 21 becomes compressed. A means of loosening the powder near the valve members 31 and 33 is provided for by a pronged member 39 fixedly attached to a portion of the air tube 20 adjacent to the valve members. When the air tube is relatively rotated by manipulating the operating member 11 in a manner to cause rotation, the powder in and near the path of the pronged member 39 will become loosened and permit the valve members 31 and 33 to operate. The pronged member 39 is of such length that the powder near the rear entrance to the powder and air passage tubes 34 also becomes loosened thus permitting the compressed air to enter the powder and air passage tubes more readily.

Additional pronged members, generally designated by the numeral 40, of the kind described in my copending application, Serial No. 96,191, 75

filed May 31, 1949, now Patent No. 2,576,804, are fixedly attached to the air tube 20 in a staggered manner and serve the purpose of loosening compacted powder in the powder storage chamber 32.

The unrestricted passage of air through the air tube 20 on the intake stroke of the operating member 11 and the return of a portion of this air in the reverse direction through the air tube, as on the discharge stroke, is accomplished by use of a flexible air tube valve 41 held in position at the rear end of the air tube by being cemented to a valve retainer 42 which is pressed into the end of the air tube. The valve retainer 42 also serves to secure the turning arm 27 in place as will readily be seen from Figures 1 and 5. On the air intake stroke the air tube valve 41 flexes into the open position by virtue of the suction created in the telescoping air chamber 21 and thus provides an unrestricted opening for the passage of air through the air tube 20. On the compression stroke the valve automatically closes to permit only a portion of the compressed air in the telescoping air chamber 21 to re-enter the air tube 20 through a suitable opening 43 in the body of the air tube valve 41, the bulk of the air being forced into the powder storage chamber 32 by passing through the openings 30. The portion of the air re-entering the air tube 20 passes through the passage chamber 13 wherein it combines cooperatively with the air and powder streams coming from the ducts 35 and thereby causes a more uniform powder in air dispersion to be ejected from the nozzle 3.

When the gun is inoperative, as when it is being stored, a closure plug 44, of resilient or other suitable material, serves to seal both the nozzle 3 and the inner orifice 16 and thus prevent powder from entering the air tube 20, or leaving the gun. Removal of the plug 44, so as to provide a continuous opening between the air tube 20 and the nozzle 3, is accomplished in a manner similar to that described in my copending application, Serial No. 123,144, filed October 24, 1949, now abandoned, in which the plug is attached to the operating member 11 by means of a flexible connecting element 45; then upon retracting the operating member at the beginning of the initial air intake stroke the plug is pulled out of its sealing position and falls into the air tube 20 as best shown in Figure 2. The connecting element 45 is fastened to a hook 46 formed on the end of a nail 47 which is first forced through the plug 44 until the head of the nail abuts the front end of the plug. Sufficient slack is provided in the connecting element 45 to permit convenient assembly of the plug 44 in the nozzle 3 and inner orifice 16. Assembly is accomplished by passing the plug 44 completely through the inner orifice 16 while the inner partition 14 is near the forward end of the gun. The front end of the plug 44 is then forced into position in nozzle 3 after first placing the inner partition 14 in its position in the gun; then the front cover 2 is pressed into place while at the same time forcing the plug to enter its sealing position in the inner orifice 16. Prior to assembly of the plug 44 in the forward end of the gun, the connecting element 45 is knotted as shown at 48 and pulled into an enlarged opening 49 in the end wall 12 of the operating member 11, after first consecutively passing the connecting element through suitable openings 50, 51, and 52 in the turning member 29, the air tube valve 41, and the valve retainer 42 respectively. A sealing strip 53 is permanently

cemented over the opening 49 thus securing the end of the connecting element 45 to the end wall 12, the opening 50 being too small to permit passage of the knot when tension is placed on the connecting element.

When the inner partition 14 is placed in position the openings 37 are kept in registry with the ducts 35 by use of positioning extensions 54 of the body of the inner partition, said extensions fitting between adjacent powder and air tube extensions 36 as can readily be seen from Figure 4. It will be apparent from Figure 1 that the rear face of the inner partition 14 abuttingly engages the forward ends of the powder and air tubes 34, and it will also be apparent that the lugs 45 press against the inside face of the front cover 2, thereby the position of the inner partition becomes fixed when the front cover is pressed into position.

The entire gun is inexpensive in construction, and all of its parts readily lend themselves to manufacture in quantity production, whereby the gun may be produced at low cost. It may be made of any desired material suitable for the purpose. Metal, plastic, paper, or more specifically, cardboard has been found very efficient and practical. The paper or cardboard may readily be waterproofed to render it immune from water and moisture, especially in those uses in which the powder might be subject to caking.

The gun herein described has been especially perfected for use as a fire extinguisher, an application which necessitates a gun capable of expelling a large amount of powder in a short time. Also, in such an application, means should be provided for completely sealing the gun against moisture and provisions made for loosening any compacted powder that may form and render the gun efficient in operation.

It is not intended that the use of this invention be limited to fire extinguishers, for by making suitable modifications in the size of the powder and air passages and openings, and eliminating the powder loosening components when they may be unnecessary such as may be the case for guns devised for light fluffy powders, a suitable simplified form can be obtained which still possesses the essential embodiments of the invention. It will therefore be apparent to those skilled in the art that I have accomplished at least the principal objects of my invention, and it will also be apparent to those skilled in the art that the embodiments herein described may be variously changed and modified without departing from the spirit of the invention, and that the invention is capable of uses and has advantages not herein specifically described; hence, it will be appreciated that the herein disclosed embodiments are illustrative, and that my invention is not limited thereto.

I claim as my invention:

1. A powder spray gun having, in combination, an elongated main tubular member, having end walls, a valved closure for one end wall and a suitably disposed discharge-air intake opening in the other end wall, an inner partition which forms a powder and air passage chamber between the discharge end wall and said inner partition, a powder storage chamber formed between the inner partition and the valved end wall, an air passage opening suitably disposed in the inner partition, an air tube passing through the valved end wall and powder storage chamber, said air tube being connected with the air passage opening in the inner partition, a plurality of powder

and air passage ducts suitably formed and disposed at the inner side of the wall of the powder storage chamber and extending from the powder and air passage chamber into a greater portion of the length of the powder storage chamber, said ducts each having a plurality of suitably spaced openings in the wall of the duct, a tubular operating member having one end wall, said operating member being mounted for slideable operation over the main tubular member, whereby a telescoping air chamber is provided between the operating member and the valved end wall of the main tubular member.

2. A powder spray gun having, in combination, an elongated main tubular member, having end walls, a valved closure for one end wall, a suitably disposed discharge-air intake opening in the other end wall, an inner partition which forms a powder and air passage chamber between the discharge end wall and said inner partition, a powder storage chamber formed between the inner partition and valved end wall, an air tube passing through the valved end wall and powder storage chamber, said air tube being connected with the air passage opening in the inner partition, a selective air control valve for the air tube, said valve being held in place by a suitable valve retainer, a plurality of powder and air passage ducts suitably formed and disposed at the inner side of the wall of the powder storage chamber and extending from the powder and air passage chamber into a greater portion of the length of the powder storage chamber, said ducts each having a plurality of suitably spaced openings in the wall of the duct, a tubular operating member having one end wall, said operating member being mounted for slideable operation over the main tubular member, whereby a telescoping air chamber is provided between the operating member and the valved end wall of the main tubular member.

3. A powder spray gun having, in combination, an elongated main tubular member having end walls, a valved closure for one end wall, a suitably formed and disposed discharge-air intake nozzle in the other end wall, an inner partition which forms a powder and air passage chamber between the discharge end wall and said inner partition, a powder storage chamber formed between the inner partition and valved end wall, a short tubular orifice suitably disposed in the inner partition, said tubular orifice cooperating pneumatically with the discharge-air intake nozzle and being in the direct path of the air stream passing through the discharge-air intake nozzle, an air tube passing through the valved end wall and powder storage chamber, said air tube being connected with the short tubular orifice in the inner partition, a selective air control valve for the air tube, said valve being held in place by a suitable valve retainer, a plurality of powder and air passage ducts suitably formed and disposed at the inner side of the wall of the powder storage chamber and extending from the powder and air passage chamber into a greater portion of the length of the powder storage chamber, said ducts each having a plurality of suitably spaced openings in the wall of the duct, a tubular operating member having one end wall, said operating member being mounted for slideable operation over the main tubular member, whereby a telescoping air chamber is provided between the operating member and the valved end wall of the main tubular member.

4. A powder spray gun having, in combination, an elongated main tubular member having end walls, a valved closure for one end wall and a suitably formed discharge-air intake nozzle centrally disposed in the other end wall, a removable inner partition which forms a powder and air passage chamber between the discharge end wall and said inner partition, said inner partition having means for being held in position, a powder storage chamber formed between the inner partition and the valved end wall, a short tubular orifice centrally disposed in the inner partition, said tubular orifice cooperating pneumatically with the discharge-air intake nozzle, an air tube passing through the center of the valved end wall and powder storage chamber, said air tube being connected with the short tubular orifice in the inner partition, a selective air control valve on the end of the portion of the air tube extending through the valved end wall, said valve being held in place by a suitable valve retainer, a plurality of powder and air passage ducts suitably formed and disposed at the inner side of the wall of the powder storage chamber and extending from the powder and air passage chamber into a greater portion of the length of the powder storage chamber, said ducts each having a plurality of suitably spaced openings in the wall of the duct, a tubular operating member having one end wall, said operating member being mounted for slideable operation over the main tubular member, whereby a telescoping air chamber is provided between the operating member and the valved end wall of the main tubular member.

5. A powder spray gun according to claim 4, wherein the valve portion of the valved end wall is comprised of a combination consisting of a space conforming member covering the air passage openings in said end wall, and a flexible member to provide resiliency to the valve combination.

6. A powder spray gun according to claim 1, wherein a pronged member is fixedly attached to a portion of the air tube adjacent the valve members of the valved end wall, and means are provided for relatively rotating the air tube in its supports when the operating member is rotatably twisted, whereby powder compacted against the valve members becomes loosened to permit the valve members to operate.

7. A powder spray gun according to claim 4, wherein the nozzle and tubular orifice are both sealed with a single plug member when the gun is inoperative, the plug being attached by suitable means to the operating member, thereby on initial operation of the gun the plug is automatically withdrawn.

8. A powder spray gun of the class described comprising means providing a powder and air passage chamber, having first and second walls, said first wall having a discharge-intake orifice, said second wall having an orifice cooperating pneumatically with said discharge-air intake orifice, means providing a telescoping air chamber a tubular air duct leading from the orifice in said second wall into said telescoping air chamber, a selective air control valve on the tubular air duct having means therein to permit only a portion of the compressed air to be returned to the inner orifice, an end wall cooperating with said tubular duct having apertures into a powder storage chamber external to said tubular duct, a plurality of powder and air passage ducts situated on the inner side of the wall of said powder storage chamber each having a plurality of aper-

tures through which a powder and air mixture may pass into the powder and air passage chamber wherein the said mixture combines with the other portion of air coming through the inner orifice, thereby causing a thoroughly dispersed mixture of powder and air to be ejected from the discharge-air intake opening.

9. In a powder spray gun of the class described, a powder storage chamber having an end wall with a valve means disposed therein, a tubular member extending through said powder storage chamber, means mounting said tubular member for rotation relative to said powder storage chamber, a plurality of powder agitating extensions integral with said tubular member and projecting into said powder storage chamber, a telescopically mounted operating member, cooperative associated projections on said operating member and said tubular member whereby initial rotary motion of said operating member agitates the powder in the powder chamber, and at least one of said powder agitating extensions being situated adjacent the valve of the valved end wall.

10. In a powder spray gun of the class described, a powder storage chamber having an end wall provided with a valve, a tubular member extending through said powder storage chamber, means supporting said tubular member for rotation relative to said powder storage chamber, at least one pronged member fixedly attached to a portion of said tubular member adjacent the valve of the valved end wall, and means provided for relatively rotating said tubular member when the operating member is twisted whereby powder compacted against the valve becomes loosened to permit the valve to operate.

11. In a powder gun of the class described, a cylinder having suitable end walls, a tubular member extending lengthwise through the cylinder, means mounting said tubular member for relative rotatable movement therein, said tubular member cooperating with the walls of the cylinder to provide an annular powder chamber, a discharge orifice at the forward end of the tubular member, an expandable operating member mounted on said cylinder for rotary and reciprocating movement thereon, said tubular member forming a discharge and intake into said expandable operating member, a valve means in the rearward end of said cylinder, a pronged member fixedly attached to said tubular member adjacent said valve member of the cylinder wall and an operative connection between said expandable operating member and said pronged member whereby initially rotary movement of said operating member will loosen any powder which has become compacted against said valve member to allow the valve to operate.

12. A powder gun according to claim 1 wherein means is provided for sealing the discharge air-intake opening and the opening in said inner partition, said means being operable to effect the opening of said discharge-air intake opening and said opening in said inner partition when the powder gun is initially operated.

13. The apparatus of claim 1 further characterized by closure member for closing said discharge-air intake opening and said air passage opening in said inner partition, said closure member being movable toward the end wall of the main tubular member having the valve closure therein for opening said discharge-air intake opening and said air passage in said inner partition, a flexible connection within said air tube between the operating member and the closure

11

member; said connection being substantially slack free when the closure member is in a position to close said discharge opening and the operating member is in a limiting position most adjacent the discharge-air opening and the air passage in the inner partition, whereby when the operating member is moved in a direction away from the discharge-air opening and the passage in the inner partition, said flexible member will exert tension on the closure member to move it to a position to open a discharge-air opening and said passage in said inner partition.

14. The apparatus of claim 13 further characterized in that said connection comprises a member which is inextensible in one direction when under tension and which is adapted for having the ends brought easily relatively adjacent one another when said connection is removed from tension.

15. A powder gun according to claim 3 wherein the short tubular orifice is of such construction

5 whereupon the discharge stroke of the operating member the discharge air in the air tube is contracted to an air jet of smaller lateral dimensions than the opening in said orifice.

16. The apparatus of claim 15 further characterized in that the short tubular orifice has a length substantially shorter than the diameter thereof.
